HANS PETERSEN, OF DAVENPORT, IOWA, ASSIGNOR TO THE LINOGRAPH COMPANY,
OF DAVENPORT, IOWA, A CORPORATION.

TRIMMING MECHANISM FOR LINOTYPE-MACHINES.

1,178,598.

Specification of Letters Patent. Patented Apr. 11, 1916.

Application filed September 3, 1915. Serial No. 48,814.

To all whom it may concern:

Be it known that I, HANS PETERSEN, a citizen of the United States of America, residing at Davenport, in the county of Scott and State of Iowa, have invented certain new and useful Improvements in Trimming Mechanism for Linotype-Machines, of which the following is a specification.

This invention relates to improvements in a trimming mechanism for a linotype machine, for shaving the roughened sides of the printing slugs after their delivery from the mold in which they are cast.

It has been proposed in the present art to provide an adjustment for the knife termed the stationary knife, but this adjustment has generally been in the form of an adjusting screw to adjust the knife, but in a single direction, after which the knife is held on its seating by means of a transverse fastening member. I am also aware that it has been proposed to place a resilient member behind the so-called stationary knife, acting in a direction opposite to an adjusting screw, but this has proven to be only a slight advantage over the form where no spring is used, as the spring merely acts as a follower for the knife when the holding screws are released, and constitutes no positive means for rigidly holding the same in its adjusted position.

It is the purpose of the present invention to provide adjusting members for the so-called stationary knife engaging opposite parts thereof, the adjusting members operating in directions opposite to each other, so that the knife may be positively adjusted, and rigidly retained in its adjusted position; the knife when adjusted is what might be termed stationary.

Structurally speaking, the preferred embodiment of the invention capable of obtaining the results above stated, comprises a pair of threaded adjusting screws arranged to engage opposite portions of the knife, these adjusting screws being associated with the knife block, so that it is only necessary to raise or lower the screws to the desired position, after which the knife is positively held by the adjusting screws.

In the accompanying drawing, I have

represented the knives as constructed and adapted to be applied to the ordinary linotype machine, but it will be readily understood that the cutting mechanism may be varied in design, form and size and applied to any special type of machine without departing from the invention.

In the drawings: Figure 1 is a side elevation of the device; and Fig. 2 is an end view of the same.

Referring more particularly to the drawings, wherein like numerals indicate corresponding parts, the numeral 1 designates what is commonly known as the knife block of a linotype machine, having a cut-out portion 2 in its face to provide a seat for the movable knife 2', and an outstanding flange 3 adapted to overlie the knife. The movable knife 2' positioned within the cut-away portion 2 is capable of an adjustment by means of the adjusting screws or bolts 5, one of these screws or bolts being placed so that they operate on the knife near each end thereof and having threaded shank portions 6 passing through the threaded apertures 7 in the outstanding flange 3. The adjusting screws are entirely disconnected from the knife and merely bear against the upper portion thereof, and at their extreme outer ends are greatly reduced in diameter to provide shoulders 7' and reduced extensions 8' upon which the gears 8 rest, these gears being retained in position by nuts 9'. The knife 2' is adjusted to the desired position by means of the adjusting screws 5 and is held in said adjusted position by the springs 9 secured to the rear portion of the knife block in any suitable manner, and pass through relatively wide transverse apertures 10 near each end of the knife block, the free ends of the springs entering the slots or recesses 10' arranged in the lower portion of the movable knife, so that this knife is at all times forced against the adjusting screws, due to the tension of the adjusting springs. A pair of gib plates 11' are fastened to the knife block 1 at each end thereof, these plates affording seating means for the movable knife, and eliminating the transverse fastening screws that are ordinarily used.

Overlying the outstanding flange 3 is the rotating gear 11, having a plurality of teeth on its periphery and at opposite ends thereof engaging the gear wheels 8 rigidly fastened to the adjustable screws 5, so that the knife is adjusted to the desired position by a rotary movement of the said gear 11, after which the gear is retained in position by a locking pin 12' passing therethrough and entering the flange portion of the knife block.

While the movable knife and its adjustments are preferably constructed in accordance with the above description, I wish it to be clearly understood that many changes and modifications to this adjusting mechanism and knife can be made without departing from the invention.

The other knife block 12 is spaced a slight distance from the block 2 and carries a so-called stationary knife 13, this knife also being spaced from the knife 2' to allow the passage of the printing slugs between the knives. In order that the stationary knife may operate successfully with the different parts of the machine subject to wear and tear at all times, it has been found that the only way in which good results can be obtained is by allowing this knife to have a slight adjustment, after which it must be rigidly retained in its adjusted position, so that no movement thereof is permitted. The knife 13 is movably fastened to the outer face of the knife block 12, and is adjusted to any position by means of the adjusting screws 14 threaded in the apertures 15 arranged in the outstanding ears or lugs 16 projecting from the knife block, and the relatively long adjustable screws 17. The adjusting screws 14 bear against the lower portion of the knife, constituting a movable seat therefor, and the relatively long threaded screws 17, which pass through the threaded apertures 18 in the flange 3, contact with the opposite portion of the knife and prevent any upward movement of the same after its adjustment. A pair of transverse fastening screws 19 pass through the enlarged apertures 20 in the block, the said apertures being of such width as to allow the vertical adjustment of fastening screws therein, the outer end of the fastening screws engaging the knife to assist in retaining the same on its seat, the said transverse fastening screws being similar to those now in use. It will be seen that when the knife 13 is adjusted, by means of the adjusting screws above described, it is positively retained and held rigid in its adjusted position, in view of the fact that the adjusting screws rest upon different portions of the knife and operate in directions opposite to each other so that all movement of the knife is prevented.

It is evident that various changes might be resorted to in the form and arrangement

of the parts described, without departing from the invention.

Having thus described the invention what I claim is:

1. A slug trimming mechanism for lino-type machines, comprising knife supporting blocks, adjustable knives thereon, a plurality of adjusting screws carried by each of said supporting blocks for adjusting the knives relative to each other, the adjusting screws for one of the knives being oppositely disposed to positively support the said knife in its adjusted position. 70

2. A slug trimming mechanism for lino-type machines, comprising knife supporting blocks, trimming knives thereon, a plurality of adjusting screws carried by said blocks and engaging the knives for retaining the same in their various adjusted positions relative to each other, the adjusting screws 80 for one of the knives being oppositely disposed and carried by the supporting blocks, the said adjusting screws engaging the upper and lower portions of the knife to positively support the same in its 85 adjusted position and prevent any bodily movement thereof. 90

3. A slug trimming mechanism for lino-type machines comprising knife supporting blocks, a pair of adjustable knives thereon, 95 means for adjusting said knives relative to each other comprising adjusting screws carried by the supporting blocks, the adjusting screws for one of the said knives being oppositely disposed and engaging different 100 portions of the knife to positively support the same in its adjusted position and prevent any bodily movement thereof. 100

4. A slug trimming mechanism for lino-type machines, comprising knife supporting 105 members, trimming knives thereon, a plurality of adjusting screws engaging said knives for retaining the same in their various adjusted positions relative to each other, the adjusting screws for one of the 110 knives being oppositely disposed and engaging the upper and lower portions of the knife to positively support the same in its adjusted position and prevent any bodily movement thereof, and a resilient member 115 adapted to engage the other of said knives to retain the same in its adjusted position. 115

5. A trimming mechanism of the character described comprising supporting members, a pair of separately adjustable cutters 120 on said members, means for adjusting said cutters relative to each other, the adjusting means for one of the cutters comprising opposed members adapted to prevent movement of the cutter in either direction relative to the other cutter and to bodily fit the same in its adjusted position, and the other of said adjusting means permitting the adjustment of its cutter toward and from the other cutter. 125 130

6. A trimming mechanism of the character described comprising supporting members, a pair of separately adjustable cutters on said members, means for adjusting said cutters relative to each other, the adjusting means for one of the cutters adapted to support and positively hold the same in its adjusted position to prevent any back and forth bodily movement thereof relative to

the other cutter, the other of said adjusting means permitting the adjustment of its cutter toward and from the other cutter.

In testimony whereof I affix my signature in the presence of two witnesses.

HANS PETERSEN.
